UNITED STATES PATENT OFFICE

2,481,271

HOLDING DEVICE FOR VOICE RECEIVERS

Matthew K. Willey, Middlefield, Conn.

Application August 24, 1946, Serial No. 692,897

3 Claims. (Cl. 179—148)

1

This invention relates to devices for holding a voice transmitting receiver in any desired position so that the user may have both hands free to handle letters, papers, etc. The device of the invention is particularly adapted for holding the voice transmitting receiver of a Dictaphone, telephone or the like.

The invention will be clearly understood from the following description in conjunction with the accompanying drawings, in which:

Fig. 1 is an elevational view, partly in section, of a device embodying the invention;

Fig. 2 is a plan view of the top portion of the device shown in Fig. 1;

Fig. 3 is an elevational view, partly in section, of the device shown in Fig. 1 with the parts in different relative positions; and

Fig. 4 is an elevational view of a device of modified form.

The device illustrated in Figs. 1, 2 and 3 comprises a weighted base 10 adapted to rest upon a flat support, such as an office floor or the top of a desk, and is provided with a threaded integral stud 11. A tubular member 12 is secured to the base 10 and for this purpose is provided at one end with internal threads 13 adapted to engage the thread stud 11. The tubular member 12 is adapted to receive a flexible member 14 which, as illustrated, comprises a metal strip wound in spiral form with its adjacent convolutions overlapping. The flexible member 14 is of the same general construction as the flexible covering commonly used for enclosing electrical insulated conduits. A disk 15 of suitable friction material, such as rubber, leather, etc. is secured to the lower end of the flexible member 14 to engage the inner wall of the tubular member 12 and slidably support the flexible member 14 in any desired longitudinal location with respect to the tubular member 12. An annular member 16 is secured to the inner wall of the tubular member 12 near its upper end to serve as a stop adapted to be engaged by the disk 15 to prevent the flexible member 14 being pulled entirely out of its supporting tube 12.

A holder H adapted to receive and hold a voice transmitting receiver is secured to the upper end of the flexible member 14. The holder H is provided with a tubular portion 18 which is internally threaded at one end to receive an externally threaded plug 19 which is secured to the upper end of the flexible member 14. A plate 20 is secured to the other end of the tube 18 and is provided with a passage 21 adapted to slidably receive a plunger 22 which projects through

2

the plate 20 from within the tube 18. A disk 23 is secured to the plunger 22 and is adapted to engage the inner wall of the tube 18 to slide therein and serves as a stop limiting the outermost position of the plunger 22. A coil spring 24 extends between the plug 19 and the disk 23 and serves to urge the plunger outwardly. A pair of plates 26 and 27 are held in spaced relation with respect to each other in a common plane 10 and in spaced relation to the plate 20 by spacer members 28 and 29 respectively and are secured to the plate 20 by bolts 30 and 31. The plates 26 and 27 are arranged so that the space between the adjacent edges thereof is directly above the plunger 22.

In the use of the device illustrated in Figs. 1, 2 and 3, a voice transmitting receiver R can be moved through the space between the plates 26 and 27, as illustrated by the dot-and-dash line position in Fig. 2, so as to depress the plunger 22 against the action of the coil spring 24 and then may be turned under the plates 26 and 27 to abut the spacer members 28 and 29, as illustrated by either the full line or broken line positions shown in Fig. 2. When in either of the two last mentioned positions and the receiver R is released, the resilient pressure of the spring 24 will cause the plunger 22 to hold the receiver in either of these positions against the plates 26 and 27. The flexible member 14 may be pulled up so as to extend out of the tubular member 12 a desired distance and then may be distorted, as illustrated in Fig. 3, so as to remain in such distorted position and locate the receiver R in a desired position with respect to the user.

The device illustrated in Fig. 4 comprises a suitable base 10' which may be weighted or not as desired. When weighted, it may rest upon a desk top, and when not weighted, may be secured to the desk top by screws S. One end of a flexible member 14' similar in construction to the flexible member 14 of the device illustrated in Figs. 1, 2 and 3, may be suitably secured to the base 10' and its other end may be suitably secured to the tubular portion 18' of the holder H', the construction of which is the same as that illustrated in Figs. 1, 2 and 3.

I claim:

1. In a device for holding a voice transmitting receiver, in combination, a support, a flexible member carried by said support, and a holder carried by said member adapted to receive and hold said receiver, said flexible member being distortible relative to said support to locate said receiver in a desired position relative to a user

and comprising a spirally wound metal strip in which the adjacent convolutions overlap, said holder comprising a pair of plates supported in spaced relation in a common plane to permit a voice transmitting receiver to be moved therebetween and turned under said plates, and resilient means adapted to hold said receiver under said plates.

2. In a device for holding a voice transmitting receiver, in combination, a support, a flexible member carried by said support, and a holder carried by said member adapted to receive and hold said receiver, said flexible member being distortible relative to said support to locate said receiver in a desired position relative to a user and comprising a spirally wound metal strip in which the adjacent convolutions overlap, said holder comprising a pair of plates supported in spaced relation in a common plane to permit a voice transmitting receiver to be moved therebetween and turned under said plates, and resilient means adapted to hold said receiver under said plates, said support including a tubular member adapted to receive said flexible member, and means for slidably supporting said flexible member in said tubular member at a desired longitudinal position with respect to said tubular member.

3. In a device for holding a voice transmitting receiver, in combination, a support, a flex-
